UNITED STATES PATENT OFFICE

JOHN BATH, OF WORCESTER, MASSACHUSETTS

GRINDING MACHINE

Application filed December 29, 1924. Serial No. 758,559.

This invention relates to a grinding machine which as to certain features may be of the general type in which the grinding wheel shaft is mounted on a relatively fixed base or standard and in which the work is supported upon a table which is slidable transversely with respect to said base or standard.

A grinding machine of this general type is shown in my prior Patent No. 1,202,018, issued to me October 24, 1916, and it is the general object of my present invention to improve the construction therein shown, thus producing a machine which is convenient to manufacture and which is effective and reliable in operation.

With these general objects in view, important features of my invention relate to the provision of an improved frame construction and arrangement; to novel devices for supporting and driving either one or two pieces of work; to an improved table driving mechanism; to an improved arrangement of bearings for the wheel shaft; to an improved work table construction; to means for axially oscillating the wheel shaft; and to other arrangements and combinations of parts which will be hereinafter described and more particularly pointed out in the appended claims.

A preferred form of the invention is shown in the drawings in which

Fig. 1 is a plan view of my improved grinding machine;

Fig. 2 is a front elevation thereof;

Fig. 3 is a right hand side elevation thereof;

Fig. 4 is a sectional front elevation, taken along the line 4—4 in Fig. 1;

Fig. 5 is a partial plan view of the bed or post of my improved machine, with the post or standard shown in section;

Fig. 6 is a detail transverse sectional elevation, taken along the line 6—6 in Fig. 4;

Fig. 7 is an enlarged left hand side elevation, looking in the direction of the arrow 7 in Figs. 1 and 4;

Fig. 8 is an enlarged plan view of the parts shown in Fig. 7;

Fig. 9 is a longitudinal sectional elevation of one of the work driving heads;

Fig. 10 is a detail sectional plan view, taken along the line 10—10 in Fig. 9;

Fig. 11 is a detail sectional elevation, showing a modified work table construction; and

Fig. 12 is a detail plan view showing the provision for dressing the grinding wheel.

Referring to the drawings, I have shown a grinding machine particularly designed for grinding cylindrical or conical work, although the machine is obviously adapted in many of its features to many other kinds of work.

My improved machine comprises a base or bed 20 having a post or standard 21 (Figs. 4 and 5) rising from a rearwardly and laterally offset portion of the base. The standard 21 may be formed as a separate member secured to the base 20 by bolts 22^a, as indicated in Fig. 4, or it may be formed integrally therewith if so desired.

The base 20 is preferably provided with bearing surfaces 22, 23 and 24, for the table slide 25, as indicated in Fig. 4. The bearings 22 and 23 may be flat plane surfaces and the bearing 24 is preferably V-shaped so as to guide the table slide 25 accurately alongside the post or standard 21.

A nut 26 (Fig. 6) is clamped to the bed 20 and is threaded to receive a feed screw 27 rotatably mounted in bearings in the table slide 25. The feed screw 27 is provided with the usual hand wheel 28 by which the table slide may be adjusted rearward and forward so as to move the work toward and from the wheel W.

The grinding wheel is mounted on a wheel shaft or spindle 30 (Fig. 1) rotatable in bearings 31, 32 and 33. The bearings 31 and 32 are mounted on a sliding plate 34 (Fig. 3) which is movable axially of the wheel shaft in guide-ways 35 and 36 by means of a feed screw 37 and nut 38, as indicated in Fig. 3.

The guide-ways 35 and 36 extend across the face of the standard 21 and also across an overhanging projecting portion 40 (Fig. 4) of the standard 21. The portion 40 is arranged substantially at the rear of the bearing surface 24 (Fig. 5) of the bed 20. It is also spaced above the bed so that there is no interference with the rearward and forward movement of the table slide 25.

The outer shaft bearing 33 (Fig. 1) is

mounted for axial adjustment, if desired, in guide-ways 41 (Fig. 7) in a frame member 42 projecting upwardly at the left hand side of the bed 20. The wheel shaft 30 is preferably provided with a tapered seat for the wheel W and may be provided with an additional tapered seat 43 for an additional wheel. The outer end of the shaft 30 is accordingly somewhat reduced in diameter, as indicated at 44.

The wheel shaft 30 is thus very firmly and rigidly supported on the post or standard 21 and receives additional support from the bearing 33 on the frame member 42. The wheel W is mounted on the shaft 30 closely adjacent the bearing 32 and the shaft 30 is of ample size and weight, so that the wheel runs with great steadiness and with much reduced vibration.

20 The bearings 31, 32 and 33 are of special construction but are not claimed specifically herein, as they form the subject matter of a companion application Serial No. 1,702, filed January 10, 1925. For the purposes of this 25 application, it is sufficient to state that each bearing includes a lower half-bearing member 46 (Fig. 7) and an upper half-bearing member 47.

30 The member 47 is carried in a cap 48 pivoted at 49 to a bracket 50 which is vertically adjustable toward and from the bearing member 46. An adjusting screw 51 also permits angular adjustment of the cap 48 relatively to the bracket 50. The spindle bearings may thus be very easily and accurately adjusted and provide firm and satisfactory support for the spindle shaft.

35 For certain purposes, especially when using very wide straight-face grinding wheels, it is desirable to slightly oscillate the grinding wheel and shaft axially during the grinding operation. For this purpose, I provide an annular groove 53 (Fig. 8) near the end of the shaft 30 and I mount an eccentric disc or cam 54 on the end of a transverse shaft 55 rotatable in bearings on the frame member 42. A worm wheel 56 (Fig. 7) is fixed to the rear end of the shaft 55 and is engaged by a worm 57 which may be rotated by a pulley 58 and belt 59 or in any other convenient manner.

40 When the worm 57 is thus rotated, the eccentric disc 54 is slowly revolved and the shaft 30 and wheel W are given a slight axial oscillation at a relatively slow speed. Such axial movement of the wheel tends to break up the surface so that the wheel operates to substantially better advantage than when rotating continuously in a single plane.

45 The wheel shaft 30 may be driven in any convenient manner but I prefer to drive the same by a pulley 60 (Fig. 1) and belt or chain 62 (Fig. 3) from a motor 64 mounted within the standard 21. A hood or casing 65 en-

closes the wheel W and supports piping 66 by which water or lubricant may be applied to the wheel and work. The shaft 30 is also protected by a cover 65^a, which is preferably mounted on the bearing member 33 and extends adjacent the bearing flange of the wheel W. The upper part of the table slide 25 (Fig. 1) is provided with a rim or band 67 to retain water which flows down through an opening 68 into a tank 69 (Fig. 5) formed in the base 20, from which tank the water or lubricant is returned by a pump (not shown) to the pipe 66.

50 A work table 70 (Fig. 2) is mounted to slide longitudinally on the table slide 25. The table 70 is preferably provided with a flat front bearing 71 (Fig. 3) and with a V-shaped rear bearing 72 on the table slide 25. The table 70 is also shown as recessed at 73 to provide a flat surface 74 which may be engaged by a hook or clamp 75 secured to a rear face of the table slide 25 and preventing lifting movement of the table 70 when the wheel W engages the work.

55 An alternative construction is shown in Fig. 11, in which the table 70^a is provided with a flat front bearing surface 76 and with a longitudinal groove in its under side adjacent the rear edge thereof, said groove providing two inclined bearing surfaces 77 and 78. The bearing surface 78 is undercut or inclined upwardly and rearwardly and the surfaces 76, 77 and 78 engage corresponding bearing surfaces on the table slide 25^a.

60 The relative positions of the wheel W and work K are indicated in Fig. 11 and it will be seen that any tendency of the table 70^a to swing forward and upward about the bearing 76 as a pivot will be offset by the engagement of the undercut surface 78 with the corresponding surface of the table slide 25^a. In this form of the invention, the table is thus held firmly on its slide without the use of a separate hook or clamp.

65 The table 70 may be moved longitudinally on the table slide 25 in any convenient or desired manner, but I have shown herein a form of hydraulic feeding mechanism therefor. This mechanism comprises a piston 80 (Fig. 2) having a piston rod 81 slideable in a bearing or stuffing box 82 at the end of a cylinder 83 and connected at its outer end to a bracket 84 fixed to the under side of the table 70. Pipes 85 and 86 connect the opposite ends of the cylinder 83 through a reversing valve 87 to a pump 88 and a return pipe 89. The reversing valve 87 is controlled by a reverse lever 90 projecting upwardly into position for engagement by dogs 91 adjustably secured on the table 70. The lever 90 may also be moved manually. The pump 88 (Fig. 2), may be driven through a sprocket 92 from any convenient source of power and a by-pass pipe 93, a relief pipe 94 and suitable valves 95, 96 and 97 are pro-

vided for controlling the operation of the hydraulic cylinder drive. A rack 98 (Fig. 2) and pinion 99 are provided for manual adjustment of the table 70.

5 I have provided special devices for rotatably supporting either one or two pieces of work upon the table 70 and these devices will now be described:—

10 When the table is to be used to rotatably support two pieces of work K and K' at the same time, I provide a double tail center or foot rest 100 (Fig. 1) which may be vertically adjustable in a stand 101 and which may be secured in adjusted position by a 15 clamping screw 102. The stand 101 is also slideable longitudinally on the table 70 and is secured in adjusted longitudinal position by a clamping member or hook 103, the bearing for the stand and the form of the hook being substantially the same as for the work 20 driving heads to be described. Two such work bearing heads 104—105 are shown in the drawings and the head 104 will now be described in detail.

25 A work center 106 (Fig. 9) is mounted in a sleeve 107 which is yieldingly pushed forward toward the work by a coil spring 108 acting against a cover plate 109. A key 110 and keyway 111 prevent angular movement 30 of the sleeve 107, and a hand lever 112 (Fig. 10) is provided for withdrawing the spindle to permit change of work. The lever 112 is pivoted in the frame of the head 104 and has a hook-like inward projection 113 which extends into a recess 114 in the sleeve 107. 35 By pulling the hand lever 112, the sleeve is withdrawn to release the work.

40 The frame of the head 104 is provided with bearing surfaces 116 and 117 (Fig. 3) and engages corresponding bearing surfaces on the table 70. A hook-like bolt or clamp 118 engages a longitudinally extended rib or projection 119 on the table 70 and holds the work head 104 firmly in desired longitudinal position.

45 For rotating the work, I provide a driver 120 (Fig. 9) mounted in a ring or face plate 121 and having a ring gear 122 secured thereto by screws 123. The plate 121 and gear 122 are rotatably mounted concentric with the sleeve 107 on the head 104 and are retained in position by a ring 124 which is positioned in a recess formed between the parts 121 and 122 and which is secured to the head 104 by 50 screws 124^a. The gear 122 is driven by a pinion 126 on a shaft 127 which may be rotated in any convenient manner and is shown herein as provided with a sprocket 128 connected by a chain 129 (Fig. 3) to a corresponding sprocket 130 on the armature shaft of an electric motor 131.

55 The work K is thus supported upon two fixed or dead centers 100 and 106 and is positively rotated by the driver 120 or by other 60 suitable connections to the driving plate 121.

It will be understood that the construction of the driving head 105 is identical with the construction of the head 104 above described.

The heads 104 and 105 are independently adjustable toward the double tail center 100, so that work of any desired length may be driven by either head. If longer work is encountered, the stand 101 may be removed and the work may be supported between the centers 106 in the driving heads. In this case, 70 the work may be driven from both ends or one of the drivers 120 may be removed so that the corresponding driving head will act merely as a tail center or support. It will also be evident that work of different characteristics may be driven by the different heads and that the motor speed of either head may be adjusted independently of the other head.

75 It is desirable that the length of the double tail center 100 should exceed the width of the wheel, so that the wheel will not engage two pieces of work at the same time. The provision of the double center and the separate driving heads has been found to greatly increase the production of my machine, as the 80 operator can stop one head and remove and replace the work driven thereby while the grinding wheel is operating upon the work driven by the second head.

85 In Fig. 12, I have indicated provision for dressing the wheel W and for this purpose have provided a bracket 220 bolted to the tail center stand 101 and positioning a wheel dressing tool 221 for engagement by the wheel. This tool when thus positioned may 90 be used to dress the wheel each time that it passes across from one piece of work K to the other piece of work K'.

95 In Fig. 3, I have indicated a support 125 at the rear of the wheel W in which support 105 a wheel dressing tool 125^a may be mounted. Actuating mechanism for this wheel dressing device is not shown herein but forms the subject matter of an additional co-pending application, Serial No. 1,703, filed January 10, 100 1925.

An opening is provided in the rear of the wheel casing or hood 65 (Fig. 3) for the operation of the tool 125^a and plates 140 and 141 are provided for partially closing this 115 rear opening. All parts of the hydraulic table operating mechanism are enclosed in a compartment 130 (Fig. 5) in the base 20 of the machine and the side of the base may be slotted as indicated at 131 (Fig. 3) to permit entrance of the pipe 86 therethrough.

120 Having thus described my invention, the numerous advantages thereof are believed to be readily apparent. The table slide 25 is provided with large and rearwardly extended bearing surfaces which permit the work to be easily and accurately adjusted toward the wheel. The wheel shaft bearings are mounted upon a post or standard of very heavy and 125 130

rigid construction and this standard is so positioned and designed that the table slide extends under the overhanging portion thereof, thus bringing the wheel above the table 5 slide while at the same time locating the wheel closely adjacent to the shaft bearings. The provision of duplicate driving heads and a double tail center greatly increases the range of work and the speed and convenience of 10 operation.

The specific construction of the guideways and supports for the sliding table are not claimed in this application but form the subject matter of a divisional application Serial 15 No. 431,949, filed February 27, 1930.

Having thus described my invention and the advantages thereof, I do not wish to be limited to the details herein disclosed, otherwise than as set forth in the claims, but what I 20 claim is:

1. In a grinding machine, a work table mounted for longitudinal movement, a double tail center secured to said table at an intermediate point, a pair of head centers 25 non-rotatably mounted at the ends of said table and each yieldingly slideable toward and from said tail centers, separate work driving mechanism associated with each of said head centers, and means engaging said 30 mechanism to yieldingly withdraw said head centers independently of said driving mechanism.

2. A grinding machine having, in combination, a wheel, a wheel shaft, a work support, a base having a plurality of parallel transverse bearing surfaces for said work support, said support being slideable on said bearing surfaces toward and from the wheel, 35 bearings for said wheel shaft, and a standard for the wheel shaft bearings rising from a laterally offset portion of said base entirely 40 at one side and end of said work support bearings.

3. A grinding machine having, in combination, a wheel, a wheel shaft, a work support, a base having a plurality of parallel transverse bearing surfaces for said work support, said support being slideable on said bearing surfaces toward and from the wheel, 45 bearings for the wheel shaft, and a standard for the wheel shaft bearings rising from a rearwardly and laterally offset portion of said base entirely at one side of said work support bearings.

4. A grinding machine having, in combination, a wheel and wheel shaft, a base having a plurality of parallel transverse bearing surfaces, a work support slideable on said bearing surfaces toward and from the wheel, 50 and a standard rising from said base entirely at one side and end of said bearing surfaces and supporting said wheel and wheel shaft, all of said bearing surfaces extending rearward out of alignment with said standard and at the same side thereof and extend-

ing rearward substantially beyond the vertical plane of said wheel shaft.

5. A grinding machine having, in combination, a wheel, a wheel shaft, a work support, a base having a plurality of parallel transverse bearing surfaces for said work support, said support being slideable on said bearing surfaces toward and from the wheel, 55 bearings for said wheel shaft, and a standard for the wheel shaft bearings rising from a laterally offset portion of said base entirely at one side of said work support bearings, and one of said shaft bearings being offset from said standard and axially overhanging one of said work support bearing surfaces 60 but spaced upwardly therefrom.

6. In a grinding machine, a wheel, a wheel shaft, a base, a standard offset from one corner thereof, bearings for said shaft on said standard, and an additional bearing for the 65 remote end of said shaft, removably mounted on said base.

7. A grinding machine having, in combination, a wheel, a wheel shaft, a base, a work support slideable on said base towards and from said wheel, a standard rising from said base and laterally offset from said work support bearings, wheel shaft bearings on said standard and a motor to drive said wheel shaft, mounted in and enclosed by said standard.

8. A grinding machine having, in combination, a wheel, a wheel shaft, a base, a work support slideable on said base towards and from said wheel, a standard rising from said base and laterally offset from said work support bearings, wheel shaft bearings on said standard and means to simultaneously adjust said wheel shaft bearings axially on said standard.

9. A grinding machine having, in combination, a wheel, a wheel shaft, a base, a work support slideable on said base towards and from said wheel, a standard rising from said base and laterally offset from said work support bearings, a plurality of wheel shaft bearings on said standard, a plate to which said bearings are secured, and means to adjust said plate axially on said standard.

10. In a grinding machine, a work table, a pair of spaced work supports and work driving heads on said table, a double tail center for two pieces of work mounted on said table intermediate said heads, said work supports and tail center providing means to support said pieces of work substantially in axial alignment, a grinding wheel common to both pieces of work, said work pieces being disposed within the range of movement of said grinding wheel, means to cause relative movement of said work and table, axially of said wheel, and means to drive each piece of work independently of the other.

11. In a grinding machine, a work table,

means to mount a plurality of pieces of work substantially in axial alignment, comprising a pair of spaced work supports and work driving heads on said table, and a double tail center for two pieces of work mounted on said table intermediate said heads, a grinding wheel common to both pieces of work, and means to cause relative movement of said work and table axially of said wheel, said work pieces being located within the range of travel of the wheel.

12. In a grinding machine, a work table mounted for longitudinal movement, separate means adjacent the ends of said table to support and rotate separate pieces of work, in substantially axial alignment with each other, means intermediate said end supports to support the adjacent ends of said pieces of work, and means to grind each piece in turn, said work pieces being located within the range of travel of the grinding means.

13. In a grinding machine, a work table mounted for longitudinal movement, means to mount a plurality of pieces of work substantially in axial alignment, comprising a double tail center for the adjacent ends of said pieces, centers to support the other ends of said work pieces, means independent of said double tail center to rotate said pieces of work, and a grinding wheel common to both pieces of work, said pieces being located within the range of travel of said grinding wheel.

14. In a grinding machine, a work table mounted for longitudinal movement to permit grinding of two pieces of work in turn, means to support said pieces substantially in axial alignment comprising a double tail center for the adjacent ends of said pieces, centers to support the other ends of said work pieces, separate work driving devices for each piece of work, and means to actuate said devices, and grinding means having a range of movement inclusive of said pieces.

15. In a grinding machine, a work table mounted for longitudinal movement, means to support a plurality of pieces of work substantially in axial alignment, comprising a double tail center for the adjacent ends of two pieces of work, centers to support the other ends of said work pieces, manual means to withdraw either of said latter centers to admit the work, and means independent of said double tail center to rotate said work pieces and grinding means having a range of movement inclusive of said pieces.

In testimony whereof I have hereunto affixed my signature.

JOHN BATH.
